CLAIM

I claim the ornamental design for a toy block, as shown and described.

DESCRIPTION

FIG. 1 is a perspective view of a toy block, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dot-dash-dot broken lines in FIGS. 4 and 5 depict the boundaries of the claim that form no part thereof.

1 Claim, 7 Drawing Sheets
